EXERCISING DEVICE

George C. Johnson, Los Angeles, Calif.

Application October 18, 1949, Serial No. 121,918

1 Claim. (Cl. 128—46)

1

This invention relates to a mechanical exercising device, and more particularly to a novel head or plate for an electrically-operated, mechanical exercising device.

It is an object of this invention to provide a novel head or plate for an exercising device of the kind to be more particularly described hereinafter operative for engagement with a selected portion of the epidermis of the human anatomy for stimulating the flow of blood through the veins and arteries in the immediately-adjacent area. The stimulation of the blood flow is active for revitalizing and increasing the well-being of the muscles, veins, nerves, glands, etc., which, under normal physical conditions, requires an extended period of time.

Another object of this invention is to provide a head or plate of this kind for a mechanical exercising device formed with spaced mounds, which, in engagement with the flesh of a patient, effect a scraping or sliding relative movement between the walls of the veins and arteries and muscle tissues for breaking up the depositions in the body. The frictional forces thus set up within the body also are active for breaking up adhesions of muscles for removing corns, bunions, etc.

With the above and other objects in view, my invention consists in the arrangement, combination and details of construction disclosed in the drawings and specification, and then more particularly pointed out in the appended claim.

In the drawings:

Figure 1 is a top plan view, partly broken away, of an exercising device having a head or plate constructed according to an embodiment of my invention;

Figure 2 is a transverse section taken on the line 2—2 of Figure 1;

Figure 3 is a top plan view of the head removed from its assembly on the exercising machine.

Figure 4 is a transverse section taken on the line 4—4 of Figure 3;

Figure 5 is a longitudinal section taken on the line 5—5 of Figure 3.

Referring to the drawings, the numeral 10 designates generally an exercising or massaging device having a head or plate 11 constructed according to an embodiment of this invention. The exercising machine 10 is of the type which is actuated by an electric motor 12 mounted on a base 14 which, in turn, may be engaged on, or supported by, a suitable fixed support, not shown in the drawings.

2

The electric motor 12 is provided with a rotatable shaft 15 having an offset or eccentric crank pin 16 on one outer end thereof. The speed rotation of the shaft 15 may be selectively controlled by any conventional speed-control means generally applicable for varying the speed of rotation of an electric motor shaft.

The vibrating plate 11, formed in the manner which I have found to be most proficient and satisfactory for use in the treatment of many diseases caused by restricted blood passages and faulty circulation and nervous tensions and pains in the body, is adapted to be rockably connected to the drive shaft 15 by connection to the crank pin 16.

A supporting brace member 17 is formed or provided with a bearing or journal 18 intermediate the length thereof for engagement with the crank pin 16. A bushing 19 is secured in the journal 18 for receiving the pin 16 and the crank pin may be retained within the journal by any suitable connecting means, not shown in the drawings, to provide for the rotation of the crank pin therein, while restraining the journal 18 from sliding off from one end of the pin. The supporting member 17 is provided with a pair of oppositely-extending side arms 20 and 21 which extend equal distances outwardly from opposite sides of the journal 18. In plan view, the brace or supporting member 17 is triangular in configuration, having the journal 18 cast, or otherwise formed, on the apex thereof. The axis of the bushing 19 is disposed along a transverse line bisecting the angle at the apex and intersecting the opposite or rear side edge midway along the length thereof. The outer ends of the supporting member 17 are formed with upwardly-opening bores or passages 21' for receiving bolts or studs 22 securing the plate 11 thereabove. A depending pedestal or pivot member 24 is formed on the lower side of the supporting member 17 and engages the upper surface of the underlying flat base 14 constituting a fulcrum for the movement of the supporting member 17 and plate 11 mounted thereon. The most desirable position of the fulcrum pedestal, or pivot center member, 24 is two-thirds of the distance between the apex 25 of the triangular connecting member 17 and the opposite side 26. This will position the pivot member one-third of the distance from the rear edge of the plate 11 to the front edge thereof along the transverse median.

The plate 11 is formed of a casting substantially elliptical in configuration having rectangular arms 27 at the opposite ends thereof. A ped-

3

estal 28 is formed on the lower side of each arm 27 and is formed with a downwardly-opening threaded bore 29 on the lower end for receiving the bolt 22 for attaching the plate 11 to the supporting member 17.

A transverse mound 30 is formed across the center portion of the supporting member 17 midway along the length thereof. Smaller mounds 31 are formed on the extreme ends of the plate 11 transversely thereof and intermediate mounds 32 are formed inwardly of the outer mounds 31 adjacent thereto.

In the use and operation of the massaging or exercising device 10 described above, the motor 12 is initially set in operation at a selected or desired speed. The rotation of the motor shaft 15 will effect the desired rocking and pivotal movement of the supporting member 17 and plate 11.

As the center mound 30 is moved sideways, 20 or longitudinally of the position of the plate 11, the two-thirds forward portion of the plate 11 is rocked transversely of the center pivot member 24 and the one-third rear portion is rocked in the opposite direction. This movement is reversed upon completion of the cycle of rotation of the crank pin 16 and the effect of this movement, when the plate 11 is engaged on the skin of a person is to move the walls of the blood veins in opposite directions, thus increasing the 30 flow of blood therethrough.

4

I do not mean to confine myself to the exact details of construction herein disclosed, but claim all variations falling within the purview of the appended claim.

5 I claim:

In an exercising and massaging device, a massage plate having an elliptical shaped center section, rectangular flanges formed on the ends of the center section, a transverse mound on said center section projecting oppositely from the skirt and transverse mounds on said flanges parallel to the mound on the center section, mounds formed on the plate intermediate the parallel mounds on the flanges and the center mounds, said last named mounds lying in divergent relation and defining ends for the center section, and means integrally formed on the flanges for attachment to a support means.

GEORGE C. JOHNSON.
